UNITED STATES PATENT OFFICE.

THOMAS HURLEY, OF BROOKLYN, NEW YORK.

DWELLING-HOUSE.

SPECIFICATION forming part of Letters Patent No. 229,416, dated June 29, 1880.

Application filed March 19, 1880. (No model.)

To all whom it may concern:

Be it known that I, THOMAS HURLEY, of Brooklyn, Kings county, New York, have invented certain new and useful Improvements 5 in Dwelling and other Houses, of which the following is a specification.

The object of this invention is to secure light and air in the sides between the adjoining houses built in continuous rows of several in 10 a block, as is now so prevalent in cities.

The invention consists of independent side walls behind a continuous front wall, separated by a space sufficient for a narrow passage at the ground, which widens upward by 15 making the walls a little sloping, so that the buildings diminish a little in width, and thus the width of the well or space for light and air is increased upwardly, which practically furnishes more light within the rooms than 20 would be had if the walls were vertical and the space equal to the greatest breadth.

In connection with sloping side walls, it is also proposed to provide substantial partition-walls between the entrance hall or passages 25 and the rooms, capable of containing or forming part of the chimney-flues, and thus provide for shifting the said flues from the side walls, where they are commonly located.

Figure 1 is partly a rear elevation and partly 30 a sectional elevation of a number of houses arranged and constructed according to the invention, the section being on the line *x x*, Fig. 2. Fig. 2 is a horizontal section of Fig. 1 on the line *y y*.

35 A represents the front wall of the block, which will be continuous along the whole block, same as in the common arrangement.

B represents the rear walls, which divide at 40 C, where they join the side walls, D, each separate house having its independent wall, and the said walls being located about the width of a narrow passage apart at the base, and sloping therefrom upward, so as to widen said space, as shown, for the better inlet of light 45 and air from the rear and top. The front wall may have windows F, if desired, for uniformity, and for light and ventilation.

It will be readily understood that the inclination of the windows G will enable more of both the direct and reflected rays of light 50 to enter than vertical windows would, and it is believed that the same is true with reference to air.

H represents the brick or other substantial partition-walls which it is proposed to employ, 55 in connection with the sloping side walls between the passages I and rooms J, to contain or form part of the chimney-flues K. Where the passage is dispensed with between upper rooms these flues may be brought together 60 into the one partition, as shown at L, over the passage below.

What I claim as my invention is—

1. A group of two or more houses constructed with two external side walls, facing each other, 65 provided with windows, and diverging from the base upward, whereby an open tapering space is formed between two adjoining houses or two adjoining sections of the same house, to provide effective light and ventilation without 70 detracting seriously from the capacity of the houses, substantially as herein set forth.

2. A group of two or more houses constructed with two diverging walls, facing each other, provided with windows, and rising from the 75 same foundation and diverging toward the roof, thereby forming an open tapering space for light and ventilation between two adjoining houses or two sections of the same house, while economizing space and material, substantially 80 as herein shown and described.

3. In the construction of two or more houses in a row or block, the said houses connected by a continuous front wall, A, common to all, and having the independent sloping side walls, 85 D, with a space or passage between, widening upward, to facilitate the inlet of light and air by the windows of said walls D, substantially as specified.

THOMAS HURLEY.
